(57) **ABSTRACT**

Apparatus, system and method for guiding a gripping tool into a structure to be gripped. In one aspect, the apparatus comprises a nubbin and a guide structure fixed to the nubbin. In a second aspect, the system comprises the apparatus and a target structure to be gripped by the gripping tool. In a third aspect, the method comprises coupling the nubbin to a target structure to be gripped by a gripping tool and moving a leading portion of the gripping tool through the apparatus and into the target structure.

**SYSTEM AND APPARATUS COMPRISING A
GUIDE FOR A GRIPPING TOOL AND
METHOD OF USING SAME**

**CROSS-REFERENCE TO RELATED
APPLICATIONS**

This application claims priority to U.S. Provisional Application No. 62/959,871, filed on Jan. 10, 2020, entitled "SYSTEM AND APPARATUS COMPRISING A GUIDE FOR A GRIPPING TOOL AND METHOD OF USING SAME," which is hereby incorporated herein by reference in its entirety as an example.

BACKGROUND OF THE INVENTION

Technical Field

The present invention relates to an apparatus for guiding a gripping tool into a structure to be gripped. In one aspect, gripping tools include, without limitation, tools that are inserted into hollow or tubular structures and used to grip the hollow or tubular structures. Examples of gripping tools include casing running tools, which can be inserted into a pipe, casing, wellbore, or a combination thereof and which can be used in drilling a wellbore. Among other uses, casing running tools can be used to rotate and reciprocate casing and liner strings while drilling a well.

Additionally, the present invention relates to applications in which tubulars and strings of tubulars need to be (i) gripped, (ii) manipulated or handled and (iii) lifted or hoisted using a tool that is coupled or connected to a device such as reaction frame or a drive head to enable both torsional and axial loads to be transferred from or into a tubular segment that is gripped. Within the field of servicing wells, constructing wells and earth drilling with service and drilling rigs the present invention relates to slips (more specifically, to slips on rigs using top drives), and relates to tubular running tools that connect to a top drive for gripping a proximal portion of tubular strings that are being removed from, placed in, made use of in, or assembled into a well bore. Tubular running tools such as these support varied functions that are advantageous to or required for the operations described, including, but not limited to, rapid engagement, rapid release, rotating, pushing, lifting or hoisting, the flow of a pressurized fluid into a string of tubulars, and the flow of the pressurized fluid out of a string of tubulars. In some embodiments of tubular running tools, the gripping range of the tubular running tools is improved or extended through the provision of linkages. See U.S. Pat. Nos. 8,454,066 B2 and 7,909,120 B2, which are both incorporated herein by reference in their entireties as examples.

Description of Related Art

It is well known that wellbores can be used to explore for and extract substances from the Earth, including natural resources such as oil, gas, or water. However, drilling a wellbore can be costly and require specialized equipment and skilled operators. Over time, devices have been developed to make drilling more efficient, for example, tubulars and nubbins. Examples of tubulars and nubbins, along with their advantages and uses, are illustrated in U.S. Pat. No. 8,348,320 B2, issued Jan. 8, 2013, entitled "LOAD RING

2

FOR LIFTING BY ELEVATOR, OF CASING HAVING NO UPSET," which is incorporated herein by reference in its entirety as an example.

The development of casing tools have also aided in decreasing costs and increasing the efficiency of drilling a wellbore and are also useful in other applications where tubulars and tubular strings must be gripped, handled and hoisted, as a person having ordinary skill in the art would understand upon reading this disclosure. Examples of the advantages and benefits provided by casing gripping tool are discussed, for example, in U.S. Pat. No. 8,454,066 B2, issued on Jun. 4, 2013, entitled "GRIP EXTENSION LINKAGE TO PROVIDE GRIPPING TOOL WITH IMPROVED OPERATIONAL RANGE, AND METHOD OF USE OF THE SAME," which patent is incorporated herein by reference in its entirety as an example, and which illustrates how gripping tools can be made and used. Further examples of gripping tools are provided in U.S. Pat. No. 7,909,120 B2, issued on Mar. 22, 2011, entitled "GRIPPING TOOL," which is incorporated herein by reference in its entirety as an example. As additional examples, gripping tools (also known as a casing running tools) are provided, for example, by Volant Oil Tools (US) Inc. having an office at 23571 Clay Road, Katy, Tex. 77449, United States. The casing running tools offered by Volant Oil Tools (US) Inc. are provided, for example, under the trade name CRTi® Casing Running Tools and CRTe® Casing Running Tools. As can be seen, gripping tools can be advantageously used to grip tubular structures, for example, the tubulars that can be used to drill wells.

Nonetheless, further advantages can be realized by using the apparatuses, systems or methods of the present disclosure. As non-exhaustive examples, some embodiments described herein can be used to reduce the skill, time, cost, or any combination thereof required to install a gripping tool in a target structure that is to be gripped. For example, in some embodiments, an apparatus of the present disclosure comprises a nubbin and a guide structure coupled to the nubbin, the guide structure being configured to guide a casing running tool into position in a pipe or casing for drilling a wellbore.

**SUMMARY OF SELECTED EMBODIMENTS OF
THE INVENTION**

In accordance with a first embodiment, an apparatus for guiding a gripping tool into a target structure to be gripped is provided. The apparatus comprises a nubbin and a guide structure fixed to the nubbin. The nubbin comprises a proximal nubbin end configured to be adjacent to the target structure, a proximal nubbin portion adjacent to the proximal nubbin end, a distal nubbin end opposite the proximal nubbin end, and a distal nubbin portion adjacent to the distal nubbin end. The proximal nubbin portion comprises a nubbin coupling configured to be coupled to the target structure. The guide structure comprises a proximal guide end adjacent to the nubbin, a proximal guide portion adjacent to the proximal guide end, a distal guide end opposite the proximal guide end, and a distal guide portion adjacent to the distal guide end, and an inner void having a cross-sectional dimension that increases from the proximal guide end to the distal guide end. The proximal guide portion is fixed to the distal nubbin portion.

In accordance with a second embodiment, a system is provided. The system comprises an apparatus for guiding a gripping tool into a target structure to be gripped and the target structure.

In accordance with a third embodiment, a method is provided for using an apparatus. The apparatus comprises a nubbin and a guide structure coupled to the nubbin. The method comprises several steps. A first step comprises coupling the nubbin to a target structure to be gripped by a gripping tool. A second step comprises moving a leading portion of the gripping tool through the apparatus and into the target structure.

Other aspects, embodiments and features of the invention will become apparent from the following detailed description of the invention when considered in conjunction with the accompanying drawings. The accompanying figures are schematic and are not intended to be drawn to scale. In the figures, each identical, or substantially similar component that is illustrated in various figures is represented by a single numeral or notation. For purposes of clarity, not every component of each embodiment of the invention shown where illustration is not necessary to allow those of ordinary skill in the art to understand the invention.

BRIEF DESCRIPTION OF THE DRAWINGS

FIG. 1 is a perspective view taken from the front, the bottom and the left of an illustrative apparatus for guiding a gripping tool.

FIG. 2 is a perspective view taken from the rear, the bottom and the right of the apparatus of FIG. 1.

FIG. 3 a perspective view taken from the front, the top, and the right of the apparatus of FIG. 1.

FIG. 4 is a front view of the apparatus of FIG. 1.

FIG. 5 is a rear view of the apparatus of FIG. 1.

FIG. 6 is a right side view of the apparatus of FIG. 1.

FIG. 7 is a left side view of the apparatus of FIG. 1.

FIG. 8 is a top view of the apparatus of FIG. 1.

FIG. 9 is a bottom view of the apparatus of FIG. 1.

FIG. 10 is a schematic cross-sectional view of the apparatus of FIG. 1 taken along Section 10-10 as depicted in FIG. 6.

FIG. 11 is an illustration of an embodiment of an apparatus comprising a nubbin and a guide structure, the apparatus being used to guide a gripping tool into position for use in drilling a wellbore.

DETAILED DESCRIPTION

In some embodiments, the apparatuses, systems and methods described in the present application solve one or more problems. For example, in some embodiments, the apparatuses, systems and methods can help reduce the skill, time, cost, or any combination thereof that is required to install a gripping tool in a target structure that is to be gripped. For example, in some embodiments, an apparatus of the present disclosure comprises a nubbin and a guide structure coupled to the nubbin. Additionally, when the nubbin is coupled, for example, by threading, to a tubular structure, the guide structure can help to guide a casing running tool into position in the tubular structure, which can be a pipe or casing in a wellbore.

In some embodiments, the apparatuses, systems, and methods described in the present disclosure can save an operator of drilling equipment significant time. For example, the task of inserting a casing running tool into position in a tubular structure can take approximately 5 to 8 minutes on average. Depending on conditions and operator skill, it is also possible for the task to take two hours or more. As an example of conditions that can effect this task, wind can

cause the casing running tool, the tubular structure, or both to sway. Accordingly, when the conditions are less optimal, an experienced operator can be required to insert a casing running tool into position, and even a skilled operator can take more time than usual. However, by using an apparatus, system or method described herein, the time required can be significantly reduced. For example, by using an apparatus comprising a nubbin and guide structure as described herein, depending on conditions, the time required to insert a casing running tool into position can be reduced to less than 5 minutes, no more than 4 minutes, no more than 3 minutes, no more than 2 minutes, no more than 1 minute or about 1 to 2 minutes, the times being either absolute times or averages over at least two insertions of one or more casing running tools, and optionally up to 10 consecutive insertions of one or more casing running tools. As used in this context, an average insertion time for consecutive insertions using an apparatus is calculated using every insertion that occurs from a first time when a first insertion occurs to a final time when a final insertion occurs. In other words, no insertions in the series of insertions are excluded from the calculation.

In some embodiments, the apparatuses, systems, and methods described in the present disclosure advantageously avoid adding significant weight to nubbins. For example, one or more operators can be required to pick up a nubbin and screw the nubbin into the end of a tubular pipe or casing, which can help protect the threads of the pipe or casing. In some embodiments, the addition of significant weight to a nubbin can be avoided by using a light weight material for the guide structure. As an example, a light weight material can be aluminium. As another example, a light weight material can be a material that has a density no greater than the density of aluminium, namely $2,710 \text{ kg/m}^3$. As another example, a light weight material can have a density of no more than 1.5, 1.4, 1.3, 1.2, or 1.1 times the density of aluminium. As another example, a light weight material can have a density of around 0.5 to 1.5 times $2,710 \text{ kg/m}^3$, or any value or range given by real numbers included in this range. In some embodiments, a light weight material can be polyurethane.

In some embodiments, the apparatuses, systems, and methods described in the present disclosure can be used to run pipes of all kinds more efficiently. For example, it can be possible to install joints of tubular at a rate of at least one joint per two minutes if conditions are typical or 1 joint every 4 minutes even if conditions are more difficult and potentially with relatively less skilled operators compared with the operators that would be required to achieve the same rates without the apparatus described in this disclosure.

Referring now to FIG. 1 through FIG. 11, an embodiment of an apparatus 0102 for guiding a gripping tool 1104 into a target structure 1102 will now be described. The apparatus 0102 comprises a nubbin 0104 and a guide structure 0106 fixed to the nubbin 0104.

The nubbin 0104 comprises a proximal nubbin end 0110 configured to be adjacent to the target structure 1102, a proximal nubbin portion 0108 adjacent to the proximal nubbin end 0110, a distal nubbin end 1002 (see FIG. 10) opposite the proximal nubbin end 0110, and a distal nubbin portion 0112 adjacent to the distal nubbin end 1002. The proximal nubbin portion 0108 comprises a nubbin coupling 0114, for example, nubbin outer screw threads 0120 as illustrated in FIG. 1. Nonetheless, a different type of couple can be used as well. For example, a magnetic coupling can be configured to be coupled to the target structure 1102.

With reference to FIG. 1 and FIG. 3, the guide structure 0106 comprises a proximal guide end 0302 adjacent to the nubbin 0104, a proximal guide portion 0304 adjacent to the proximal guide end 0302, a distal guide end 0308 opposite the proximal guide end 0302, a distal guide portion 0306 adjacent to the distal guide end 0308, and an inner void 0312. The inner void 0312 can be in the form of a conduit and can have a cross-sectional dimension 0310 (e.g., diameter) that increases from the proximal guide end 0302 to the distal guide end 0308. As illustrated in the embodiment of FIG. 1 and FIG. 3, the proximal guide portion 0304 is fixed to the distal nubbin portion 0112. This can be done with screws, or fasteners of any kind known in the art. Additionally, this can be accomplished by adhering the proximal guide portion to the distal nubbin portion. As another example, this can be accomplished by making the guide structure and the nubbin integral so that they form a single continuous structure.

With reference again to FIG. 1, the nubbin 0104 can comprise a nubbin collar 0116. As can be seen, in some embodiments, the nubbin 0104 or the nubbin collar 0116 comprises a plurality of collar apertures 0118 comprising a first collar aperture opposite a second collar aperture, both apertures being configured to receive a rod. Furthermore, the central axis of the first collar aperture 0118 and the central axis of the second collar aperture 0118 can be approximately perpendicular to the central axis 0402 of the nubbin 0104.

In some embodiments, the nubbin 0104 comprises an external screw thread 0120, which can be located between the nubbin collar 0116 and the proximal nubbin end 0110.

In some embodiments, the nubbin 0104 comprises a non-threaded outer surface 0122 without screw thread. The non-threaded outer surface 0122 can be located between the external screw thread 0120 and the proximal nubbin end 0110. As illustrated in FIG. 1, the non-threaded outer surface 0122 can have an outer dimension (e.g., diameter) that is smaller than the outer dimension (e.g. diameter) of the external screw thread 0120.

With reference now to FIG. 3, in some embodiments, the guide structure 0106 has a truncated conical shape or a bell shape. However, other shapes for the guide structure are also possible, for example, a hemispherical shape. Additionally, as illustrated, the inner surface of the guide structure 0106 can have a truncated conical shape or a bell shape, although other shapes, for example, a hemispherical shape are also possible. Accordingly, in some embodiments, the system can comprise any component described in this disclosure and any combination of components described in this disclosure.

Referring to FIG. 11, a system comprising an apparatus 0102 as described herein will now be described. As illustrated, the system can comprise the target structure 1102, the gripping tool 1104, a cylindrical rod (e.g., having a length long enough to pass through both a first aperture 0118 and a second aperture 0118 on the nubbin collar 0116); or a combination thereof. In some embodiments, the system can comprise any component described in this disclosure.

With further reference to FIG. 11, a method of using an apparatus 0102 as described herein will now be described. As illustrated, the apparatus 0102 comprises a nubbin 0104 and a guide structure 0106 coupled to the nubbin 0104. The method comprises several steps. A first step comprises coupling the nubbin 0104 to a target structure 1102 to be gripped by a gripping tool 1104. A second step comprises moving a leading portion 1110 of the gripping tool 1104 through the apparatus 0102 and into the target structure 1102. For example, the leading portion 1110 of the gripping tool 1104 can be moved from a first position outside the

guide structure 0106 to a second position inside the guide structure 0106, then from the second position inside the guide structure 0106 to a third position inside the nubbin 0104, and then from the third position inside the nubbin 0104 to a fourth position inside the target structure 1102.

As illustrated, the target structure 1102 can comprise a tubular or plurality of tubulars, which can be interconnected tubulars that form a continuous conduit within the tubulars. Additionally as illustrated, the target structure can be located at a site for drilling a wellbore. As examples, the target structure 1102 can comprise a pipe, a plurality of pipes or casing.

Additional Embodiments

The following clauses include descriptive embodiments that are offered as further support of the disclosed invention:

1. An apparatus 0102 for guiding a gripping tool 1104 into a target structure 1102 to be gripped, the apparatus 0102 comprising:

a nubbin 0104; and

a guide structure 0106 coupled or fixed (e.g., permanently fixed, or reversibly coupled) to the nubbin 0104;

the nubbin 0104 comprising a proximal nubbin end 0110 configured to be adjacent to the target structure 1102 (optionally configured to be coupled, directly or indirectly, to the target structure 1102), a proximal nubbin portion 0108 adjacent to the proximal nubbin end 0110, a distal nubbin end 1002 opposite the proximal nubbin end 0110, and a distal nubbin portion 0112 adjacent to the distal nubbin end 1002; the nubbin 0104, the proximal nubbin end 0110, the proximal nubbin portion 0108, the distal nubbin portion 0112, or any combination thereof comprising a nubbin coupling 0114 or couplings (e.g., nubbin inner screw threads 0120 or nubbin outer screw threads 0120, component configured to mate with the target coupling, a bolt, bolts, a magnetic material, magnetic materials, a magnet, magnets or any combination thereof) configured to be coupled (e.g., directly or indirectly) to the target structure 1102 (e.g., a target coupling comprising target outer screw threads, target inner screw threads, a magnetic material or a magnet configured to engage the nubbin coupling 0114);

the guide structure 0106 comprising a proximal guide end 0302 adjacent to the nubbin 0104, a proximal guide portion 0304 adjacent to the proximal guide end 0302, a distal guide end 0308 opposite the proximal guide end 0302, a distal guide portion 0306 adjacent to the distal guide end 0308, and an inner void (e.g., conduit) having a cross-sectional dimension 0310 (e.g., diameter or other dimension perpendicular to a central axis of the guide structure 0106, a central axis 0402 of the nubbin 0104 or both) that increases (e.g., gradually increases, smoothly increases, or both) from the proximal guide end 0302 to the distal guide end 0308, the proximal guide portion 0304 being coupled or fixed (e.g., permanently or reversibly fixed, or permanently or reversibly coupled) to the distal nubbin portion 0112;

optionally the nubbin 0104 comprises a nubbin collar 0116 (e.g., cylindrical collar, collar protruding outwardly from the nubbin 0104, collar with a larger outer diameter than other portions of the nubbin 0104, collar with a larger outer diameter than all other portions of the nubbin 0104 or any combination thereof), optionally the distal nubbin portion 0112 comprises the nubbin collar 0116, optionally the nubbin collar 0116 is located adjacent to the distal nubbin end 1002, optionally the nubbin 0104 or the nubbin collar 0116 comprises a plurality of collar apertures 0118 configured to receive a rod, optionally the plurality of apertures

60 than other portions of the nubbin 0104, collar with a larger outer diameter than all other portions of the nubbin 0104 or any combination thereof), optionally the distal nubbin portion 0112 comprises the nubbin collar 0116, optionally the nubbin collar 0116 is located adjacent to the distal nubbin end 1002, optionally the nubbin 0104 or the nubbin collar 0116 comprises a plurality of collar apertures 0118 configured to receive a rod, optionally the plurality of apertures

comprise a first collar aperture **0118** and a second collar aperture **0118** opposite the first collar aperture, the first collar aperture **0118** and the second collar aperture **0118** configured so that a rod (e.g., straight rod, cylindrical rod, rod long enough to extend through both the first collar aperture **0118** and the second collar aperture **0118** simultaneously, or a combination thereof) can pass through or be inserted into both the first collar aperture **0118** and the second collar aperture simultaneously, optionally the first collar aperture **0118** and the second collar aperture **0118** are cylindrical, optionally the central axis of the first collar aperture **0118** and the central axis of the second collar aperture **0118** are within 15, 10, 5, 4, 3, 2 or 1 degrees of perpendicular to the central axis **0402** of the nubbin **0104**;

optionally the nubbin **0104** comprises an external screw thread **0120**, optionally the external screw thread **0120** is located between the nubbin collar **0116** and the proximal nubbin end **0110**;

optionally the nubbin **0104** comprises a non-threaded outer surface **0122** (e.g., round outer surface, or somewhat cylindrical outer surface) without screw thread, optionally the non-threaded outer surface **0122** is located between an external screw thread **0120** of the nubbin **0104** and the proximal nubbin end **0110**, optionally the non-threaded outer surface **0122** has an outer dimension (e.g., diameter or optionally largest dimension perpendicular to the central axis **0402** of the nubbin **0104** for non-threaded outer surfaces **0122** having shapes with non-circular cross-sections) that is smaller than the outer dimension (e.g. diameter) of the external screw thread **0120**; and

optionally the guide structure **0106** has a truncated conical shape, a bell shape or a hemispherical shape, optionally the inner surface of the guide structure **0106** has a truncated conical shape, a bell shape or a hemispherical shape.

2. The apparatus **0102** of any preceding clause, wherein:

optionally the guide structure **0106** is configured so that when the central axis **0402** of the nubbin **0104** is oriented vertically, an inner surface of the truncated conical shape is oriented at an angle of 30 degrees+/-15, 10, 9, 8, 7, 6, 5, 4, 3, 2, or 1 degrees above horizontal; optionally the guide structure **0106** is configured so that when the central axis **0402** of the nubbin **0104** is oriented vertically, an inner surface of the truncated conical shape is oriented at an angle of 25 degrees+/-15, 10, 9, 8, 7, 6, 5, 4, 3, 2, or 1 degrees above horizontal.

3. The apparatus **0102** of any preceding clause, wherein:

optionally the nubbin **0104** has an inner diameter equal to 8 and $\frac{5}{8}$ inches+/-5, 4, 3, 2, 1, $\frac{1}{8}$, $\frac{3}{8}$, $\frac{1}{2}$ or $\frac{1}{4}$ inches; optionally the nubbin **0104** has an inner diameter equal to 9 and $\frac{5}{8}$ inches+/-5, 4, 3, 2, 1, $\frac{1}{8}$, $\frac{3}{8}$, $\frac{1}{2}$ or $\frac{1}{4}$ inches; optionally the nubbin **0104** has an inner diameter equal to 10 and $\frac{5}{8}$ inches+/-5, 4, 3, 2, 1, $\frac{1}{8}$, $\frac{3}{8}$, $\frac{1}{2}$ or $\frac{1}{4}$ inches; optionally the nubbin **0104** has an inner diameter equal to 11 and $\frac{5}{8}$ inches+/-5, 4, 3, 2, 1, $\frac{1}{8}$, $\frac{3}{8}$, $\frac{1}{2}$ or $\frac{1}{4}$ inches;

optionally the nubbin **0104** has an outer diameter equal to 10 and $\frac{5}{8}$ inches+/-5, 4, 3, 2, 1, $\frac{1}{8}$, $\frac{3}{8}$, $\frac{1}{2}$ or $\frac{1}{4}$ inches; optionally the nubbin **0104** has an outer diameter equal to 11 and $\frac{5}{8}$ inches+/-5, 4, 3, 2, 1, $\frac{1}{8}$, $\frac{3}{8}$, $\frac{1}{2}$ or $\frac{1}{4}$ inches; optionally the nubbin **0104** has an outer diameter equal to 12 and $\frac{5}{8}$ inches+/-5, 4, 3, 2, 1, $\frac{1}{8}$, $\frac{3}{8}$, $\frac{1}{2}$ or $\frac{1}{4}$ inches; optionally the nubbin **0104** has an outer diameter equal to 13 and $\frac{5}{8}$ inches+/-5, 4, 3, 2, 1, $\frac{1}{8}$, $\frac{3}{8}$, $\frac{1}{2}$ or $\frac{1}{4}$ inches;

optionally the proximal guide end **0302** has an inner diameter equal to 10 and $\frac{5}{8}$ inches+/-5, 4, 3, 2, 1, $\frac{1}{8}$, $\frac{3}{8}$, $\frac{1}{2}$ or $\frac{1}{4}$ inches; optionally the proximal guide end **0302** has an inner diameter equal to 11 and $\frac{5}{8}$ inches+/-5, 4, 3, 2, 1, $\frac{1}{8}$, $\frac{3}{8}$, $\frac{1}{2}$ or $\frac{1}{4}$ inches; optionally the distal guide end **0308** has

an inner diameter of 16 and $\frac{5}{8}$ inches+/-5, 4, 3, 2, 1, $\frac{1}{8}$, $\frac{3}{8}$, $\frac{1}{2}$ or $\frac{1}{4}$ inches; optionally the distal guide end **0308** has an inner diameter of 17 and $\frac{5}{8}$ inches+/-5, 4, 3, 2, 1, $\frac{1}{8}$, $\frac{3}{8}$, $\frac{1}{2}$ or $\frac{1}{4}$ inches; and

optionally the proximal guide end **0302** has an outer diameter equal to 12 and $\frac{5}{8}$ inches+/-5, 4, 3, 2, 1, $\frac{1}{8}$, $\frac{3}{8}$, $\frac{1}{2}$ or $\frac{1}{4}$ inches; optionally the proximal guide end **0302** has an outer diameter equal to 13 and $\frac{5}{8}$ inches+/-5, 4, 3, 2, 1, $\frac{1}{8}$, $\frac{3}{8}$, $\frac{1}{2}$ or $\frac{1}{4}$ inches; optionally the distal guide end **0308** has an outer diameter of 18 and $\frac{5}{8}$ inches+/-5, 4, 3, 2, 1, $\frac{1}{8}$, $\frac{3}{8}$, $\frac{1}{2}$ or $\frac{1}{4}$ inches; optionally the distal guide end **0308** has an outer diameter of 19 and $\frac{5}{8}$ inches+/-5, 4, 3, 2, 1, $\frac{1}{8}$, $\frac{3}{8}$, $\frac{1}{2}$ or $\frac{1}{4}$ inches.

3. The apparatus **0102** of any preceding clause, wherein:

optionally the length **1004** of the nubbin **0104**, as measured along the central axis **0402** of the nubbin **0104**, is 6 and $\frac{5}{8}$ inches+/-5, 4, 3, 2, 1, $\frac{1}{8}$, $\frac{3}{8}$, $\frac{1}{2}$ or $\frac{1}{4}$ inches; and

optionally the length **1006** of the guide structure **0106**, as measured along the central axis **0402** of the nubbin **0104**, is 1 and $\frac{5}{8}$ inches+/-1, $\frac{1}{8}$, $\frac{3}{8}$, $\frac{1}{2}$ or $\frac{1}{4}$ inches.

4. The apparatus **0102** of any preceding clause, wherein the apparatus **0102** comprises a first material and a second material;

optionally wherein the nubbin **0104** comprises, consists essentially of or consists of the first material, the second material or a combination thereof;

optionally wherein the guide structure **0106** comprises, consists essentially or consists of the first material, the second material or a combination thereof;

optionally wherein the first material is more dense than the second material;

optionally wherein the first material is configured to be rigid;

optionally wherein the second material is configured to be rigid;

optionally wherein the first material is metal (e.g., a metal alloy, steel, stainless steel, carbon steel, aluminium, or any combination thereof), polymer, rubber, plastic, thermoplastic, polyurethane or any combination thereof; and

optionally wherein the second material is metal (e.g., a metal alloy, steel, stainless steel, carbon steel, aluminium or any combination thereof), polymer, rubber, plastic, thermoplastic, polyurethane or any combination thereof; optionally wherein the second material has a density equal to no more than 2,710 kg/m³, a density of no more than 1.5, 1.4, 1.3, 1.2, or 1.1 times 2,710 kg/m³, a density of at least 0.5, 0.6, 0.7, 0.8 or 0.9 times 2,710 kg/m³, a density of around 0.5 to 1.5 times 2,710 kg/m³, or any combination thereof.

5. A system comprising the apparatus **0102** of any preceding clause:

optionally the system comprising the target structure **1102**;

optionally the system comprising the gripping tool **1104**;

optionally the system comprising a cylindrical rod (e.g., having a length long enough to pass through both a first aperture **0118** and a second aperture **0118** positioned opposite the first aperture on the nubbin or the nubbin collar **0116**); and

optionally the system comprising any component or any combination of components described in this disclosure.

6. A method of using an apparatus **0102** (e.g., for guiding a gripping tool **1104** into a target structure **1102** to be gripped (e.g., a tubular structure, pipe or casing, which can optionally be used to drill a wellbore)), wherein the apparatus **0102** comprises a nubbin **0104** and a guide structure **0106** coupled to the nubbin **0104**, the method comprising:

optionally coupling the nubbin **0104** to a target structure **1102** (e.g., tubular structure, tubular structures, tubular, tubulars, pipe, pipes, casing, or any combination thereof) to be gripped by a gripping tool **1104** (e.g., by using a nubbin screw thread **0120** on an interior of the nubbin **0104** to couple to a target screw thread **1106** on the exterior of the target structure **1102**, or by using a nubbin screw thread **0120** on an exterior of the nubbin **0104** to connect to a target screw thread **1106** on the interior of the target structure **1102**, optionally wherein the target structure **1102** comprises a plurality of structures **1108** that have been coupled in series to form a continuous void inside the plurality of structures **1108**);

optionally moving a leading portion **1110** of the gripping tool **1104** through the apparatus **0102** and into the target structure **1102**, optionally from a first position outside the guide structure **0106** to a second position inside the guide structure **0106**, from the second position inside the guide structure **0106** to a third position inside the nubbin **0104**, from the third position inside the nubbin **0104** to a fourth position inside the target structure **1102**;

optionally wherein the apparatus **0102** is the apparatus **0102** of any preceding clause;

optionally wherein the system of any preceding clause comprises the apparatus **0102** of any preceding clause;

optionally wherein the target structure **1102** comprises a tubular or plurality of tubulars (e.g., interconnected tubulars) located at a site for drilling a wellbore; and

optionally wherein the target structure **1102** comprises a pipe or casing.

Although embodiments have been described in this disclosure, including for example the drawings, using a nubbin **0104** and a guide structure **0106** with specific shapes, the nubbin **0104** and guide structure **0106** are not limited to these respective shapes. For example, in some embodiments the edges, intersections and surfaces of any component or structure described herein can be can be planar, rounded, chamfered, at right angles, non-planar, not rounded, not chamfered, not at right angles or a combination thereof.

Although embodiments have been described in this disclosure, including for example the drawings, using an apparatus **0102** that is a single continuous structure, the apparatus **0102** can instead be made of separate components that are combined (e.g., fixed, either permanently or reversibly, or coupled, either permanently or reversibly). For example, although the guide structure **0106** is illustrated as forming a single continuous structure with the nubbin **0104**, the guide structure **0106** can be combined (e.g., fixed, either permanently or reversibly, or coupled, either permanently or reversibly) with the nubbin **0104** in various ways.

Although embodiments have been described in this disclosure, including for example the drawings, using specific dimensions and angles, in other embodiments, any dimension or selection of dimensions can be changed (either increased or decreased in size) by multiplying the dimension by any factor and any other dimension or dimensions can remain the same. In some embodiments, the factor can be 0.1, 0.2, 0.3, 0.4, 0.5, 0.6, 0.7, 0.8, 0.9, 1.0, 1.1, 1.2, 1.3, 1.4, 1.5, 1.6, 1.7, 1.8, 1.9 or 2.0. In some embodiments, the invention can be stretched or shrunk proportionally parallel to or perpendicular to the central axis **0402** of the nubbin **0104** or the guide structure **0106** or both. In some embodiments, as illustrated in FIG. 1, the central axis **0402** of the nubbin **0104** and the central axis of the guide structure **0106** can be concentric.

Although embodiments have been described using the word "comprising," additional embodiments can be created

by replacing the word "comprising" with "consisting essentially of" or "consisting of" Additional embodiments can be created by replacing the word "comprising," with comprising 1, 2, 3, 4, 5, 10, 20, 30, 40, 50, 60, 70, 80, 90, 95, 96, 97, 98, or 99 wt. % and up to 100 wt. % of the component described.

Although embodiments have been described using the term "fixed," "coupled" or conjugates thereof, additional embodiments can be created by replacing either term or conjugates thereof with "fixed," "permanently fixed," "reversibly fixed," "coupled," "permanently coupled," "reversibly coupled," combinations thereof or conjugates thereof. Examples of fixing include fixing components relative to each other in position (e.g., relative distance between adjacent outer surfaces of the components or relative distance between the centers of mass for the components, or any combination thereof), orientation, arrangement, connectivity or any combination thereof. Examples of coupled include fixedly coupled, non-fixedly coupled, adhered, rotatably coupled, screwed together, mated, slidably coupled, snapped together, bolted together, or other options for connecting two structures.

Although embodiments have been described using a first range with a first set of end points, additional embodiments can be created by replacing the first range with a narrower range whose endpoints are selected from any value contained in the first range.

Although embodiments have been described using a specific direction relative to a reference direction, additional embodiments can be created by indicating that the specific direction can vary from the reference direction by no more than 45, 40, 35, 30, 25, 20, 15, 10, 5, 4, 3, 2 or 1 degrees.

Although embodiments have been described using a specific angle, additional embodiments can be created by indicating that the specific angle can vary from the reference direction by no more than 45, 40, 35, 30, 25, 20, 15, 10, 5, 4, 3, 2 or 1 degrees. Additionally, the angle of the walls of the guide structure **0106** to the central axis of the guide structure can change by +/- 15, 10, 9, 8, 7, 6, 5, 4, 3, 2 or 1 degrees from any value described in this disclosure.

Although embodiments have been described using specific dimensions, in additional embodiments, the dimensions can be different. For example, the dimensions of the apparatus can be shrunken or enlarged. To illustrate, additional embodiments can be formed by changing the length along the central axis, the inner diameter of the nubbin **0104** at any given point or any selection of points, the outer diameter of the nubbin at any given point or any selection of points, the inner diameter of the guide structure **0106** at any given point or any selection of points, or the outer diameter of the guide structure at any given point or any selection of points, or any combination thereof can vary by +/- 50, 45, 40, 35, 30, 25, 20, 15, 10, or 5, 4, 3, 2 or 1% of the values described in this disclosure.

Some embodiments have been described using optional elements. One of the optional elements, a selection of any of the optional elements, or all of the optional elements can be included in an embodiment, but inclusion of the optional elements in the embodiment is not required. Additionally, any combination of the optional elements can be included in the embodiment.

Although the apparatus has been illustrated as comprising a nubbin **0104** that can be coupled to a target structure **1102**, pipe, casing or tubular using a threaded coupling, in some embodiments, the apparatus or nubbin **0104** can be coupled to a target structure **1102**, pipe, casing or tubular using magnetic attraction. For example, the apparatus can exclude

11

a nubbin 0104 and can instead comprise a different structure with a magnetic coupling configured to be coupled to a target structure 1102, pipe, casing or tubular using magnetic attraction. As another example, the apparatus can comprise a nubbin 0104 that is configured to be coupled to a target structure 1102, pipe, casing or tubular using magnetic attraction. For example, the nubbin 0104 can comprise a magnet that is configured to be coupled to a target structure 1102, pipe, casing or tubular using magnetic attraction.

Although the invention hereof has been described by way of preferred embodiments, it will be evident that other adaptations and modifications can be employed without departing from the spirit and scope thereof. The terms and expressions employed herein have been used as terms of description and not of limitation; and thus, there is no intent of excluding equivalents, but on the contrary it is intended to cover any and all equivalents that may be employed without departing from the spirit and scope of the invention.

What is claimed is:

1. A method of using an apparatus for guiding a gripping tool into a target structure to be gripped, the apparatus comprising:

a nubbin; and

a guide structure fixed to the nubbin and configured to guide the gripping tool into a position within the target structure where the gripping tool can directly contact and grip the target structure;

the nubbin comprising a proximal nubbin end configured to be adjacent to the target structure, a proximal nubbin portion adjacent to the proximal nubbin end, a distal nubbin end opposite the proximal nubbin end, and a distal nubbin portion adjacent to the distal nubbin end; the distal nubbin end and at least a part of the distal nubbin portion forming a nubbin collar, the nubbin collar protruding outwardly from an adjacent surface of the nubbin, the adjacent surface of the nubbin being located between the nubbin collar and the proximal nubbin end;

the proximal nubbin portion comprising a nubbin coupling and a non-threaded outer surface, the nubbin coupling configured to be coupled to the target structure, the nubbin coupling positioned between the nubbin collar and the proximal nubbin end, the nubbin coupling comprising an external screw thread, and the non-threaded outer surface being located between the external screw thread of the nubbin coupling and the proximal nubbin end, the non-threaded outer surface having an outer diameter that is smaller than the outer diameter of the external screw thread;

the guide structure comprising a proximal guide end adjacent to the nubbin, a proximal guide portion adjacent to the proximal guide end, a distal guide end opposite the proximal guide end, and an inner void having a cross-sectional dimension that increases from the proximal guide end to the distal guide end, the cross-sectional dimension being measured perpendicular to a central axis of the nubbin;

the proximal guide portion being fixed to the distal nubbin portion; and

the inner void forming a conduit in the guide structure, the conduit being circumferentially continuous around a cross-section of the void at a portion of the void where the cross-sectional dimension of the void is larger than the outer diameter of the nubbin;

the method comprising:

12

coupling the nubbin to the target structure to be gripped by the gripping tool;

moving a leading portion of the gripping tool through the apparatus and into the target structure so that at least the leading portion of the gripping tool is positioned to directly grip the target structure; and using the gripping tool to directly grip the target structure.

2. The method of claim 1, wherein the nubbin collar comprises a plurality of collar apertures, the plurality of collar apertures comprising a first collar aperture and a second collar aperture opposite the first collar aperture, the first collar aperture and the second collar aperture configured to receive a cylindrical rod that is long enough to extend simultaneously through both the first collar aperture and the second collar aperture.

3. The method of claim 2, wherein the first collar aperture and the second collar aperture are configured so that a central axis of the first collar aperture and a central axis of the second collar aperture are each within 15 degrees of perpendicular to the central axis of the nubbin.

4. The method of claim 1, wherein the guide structure has a truncated conical shape.

5. The method of claim 4, wherein the guide structure is configured so that when the central axis of the nubbin is oriented vertically, an inner surface of the truncated conical shape is oriented at an angle of 20-40 degrees above horizontal.

6. The method of claim 1, wherein the nubbin has an inner diameter equal to 8 and $\frac{1}{8}$ inches $\pm$ 5 inches.

7. The method of claim 1, wherein the nubbin has an outer diameter equal to 10 and $\frac{1}{8}$ inches $\pm$ 5 inches.

8. The method of claim 1, wherein the proximal guide end has an inner diameter equal to 10 and $\frac{1}{8}$ inches $\pm$ 5 inches.

9. The method of claim 1, wherein the proximal guide end has an outer diameter equal to 12 and $\frac{1}{8}$ inches $\pm$ 5 inches.

10. The method of claim 1, wherein the distal guide end has an inner diameter equal to 16 and $\frac{1}{8}$ inches $\pm$ 5 inches.

11. The method of claim 1, wherein the distal guide end has an outer diameter equal to 18 and $\frac{1}{8}$ inches $\pm$ 5 inches.

12. The method of claim 1, wherein the guide structure comprises aluminum.

13. The method of claim 1, wherein the target structure comprises a pipe or casing.

14. The method of claim 1, the proximal guide portion being fixed to the nubbin collar; and the conduit being circumferentially continuous around the cross-section of the void for at least a portion of the proximal guide portion.

15. The method of claim 14, wherein the cross-sectional dimension is a diameter.

16. The method of claim 1, wherein an inner surface of the nubbin is non-threaded.

17. The method of claim 1, wherein the moving step comprises:

moving the leading portion of the gripping tool from a first position outside the guide structure to a second position inside the guide structure, from the second position inside the guide structure to a third position inside the nubbin, from the third position inside the nubbin to a fourth position inside the target structure.

18. The method of claim 1, wherein the target structure comprises a tubular located at a site for drilling a wellbore.
